UNITED STATES PATENT OFFICE.

EUGENE OURY, OF CHERBOURG, ASSIGNOR TO JEAN ALBAN LANNES, OF PARIS, FRANCE.

MANUFACTURE OF CHAINS.

SPECIFICATION forming part of Letters Patent No. 273,139, dated February 27, 1883.

Application filed November 3, 1882. (No model.) Patented in France March 17, 1881, No. 141,728; in Belgium June 27, 1881, No. 55,016, and in Germany June 28, 1881, No. 16,652.

To all whom it may concern:

Be it known that I, EUGENE OURY, a citizen of the French Republic, and a resident of Cherbourg, (Department of the Manche,) France, have invented certain Improvements 5 in the Manufacture of Chains, of which the following is a specification.

My invention relates to the manufacture of chains from solid bars without a weld; and it 10 consists, essentially, in first rolling or cutting out a bar of the solid metal having a transverse section in the form of a cross—that is to say, the bar has four ribs, extending its entire 15 length, of the same thickness, and having the opposite re-entering angles equal. Preferably all the angles are right angles. From a bar thus formed portions of the ribs are cut away at intervals to separate or divide off the links, and these cut-away portions or recesses alternate, so that before the adjacent links are separated entirely the bar presents the appearance 20 of a solid or rigid chain. The links are then separated, so as to give to the chain the customary flexibility, and this is effected by 25 punching or cutting out the surplus metal, as will be hereinafter described. The links may then be shaped in dies of peculiar construction, which will also be described hereinafter.

In the drawings, which serve to illustrate 30 my invention and the modes and means employed for putting it into effect, Figure 1 shows a cross-section of the bar from which the chain is formed, and also the holes pierced diagonally through from angle to angle for separating the links. Figs. 2 and 3 represent, 35 respectively, a plan and side view of a chain which is being constructed according to my method, illustrating all the various transformations through which the bar passes from the solid to the chain of finished links. Figs. 40 4 to 15, inclusive, illustrate the various tools employed in forming the chain, which will be referred to hereinafter in describing the mode of manufacture.

As before stated, a bar of metal is formed 45 having a cross-section similar to that shown in Fig. 1, the four ribs being arranged oppositely, and having the same thickness. The links A are formed from the ribs by cutting away parts

of the same at *a* and *a'*, the recesses *a* being 50 arranged opposite each other, and the recesses *a'* opposite each other, and the pairs *a* and *a'* being arranged to alternate. For cutting out the ribs to form these recesses I employ the tool shown in vertical section in Fig. 4 and in 55 horizontal section in Fig. 5. This tool consists of two laterally-cutting punches, *b b*, connected at their upper end, and arranged to enter a matrix or die, *c*, of the proper shape. Room is left between the punches for the ribs that stand 60 upright while the other ribs are being cut away.

The next step is to punch the holes D D diagonally through the links at the points clearly 65 shown in the first three figures of the drawings. The tool I employ for this purpose is illustrated in Figs. 6, 7, 8, and 9, the first being an end view, the second a side view, the third a cross-section on line 8-8 in Fig. 7, and the fourth a detached view, which will be explained. 70

E is an interior cylinder, fixed in the frame E', which bears the four spring-punches *d d*.

F is an exterior cylinder, mounted rotatively 75 in the frame E', provided with collars to prevent longitudinal movement, and with a driving-pulley, G, keyed to it. This cylinder F is provided also with splines H, on which is mounted to slide a cylinder, I, which has cams K K', to wipe over the outer ends of the punches, or over shoulders thereon, and to 80 press them radially inward.

L is an abutment on the frame E', and *b' b'* are cams on the cylinder I, which strike, as the cylinder rotates, the abutment L, and impart a longitudinal reciprocating motion to the 85 cylinder I. The cylinder I advances or recedes after the cams *k k'* have acted on the punches *d d*. The abutment L (shown detached in plan in Fig. 9) is arranged to slide in a part of the main frame, and is provided 90 with a suitable handle for moving it in or out.

The next step is to groove out the metal at J from both sides of the link and then to punch out the tie-pieces M. This last is done by means of a tool shown in Figs. 10 and 11, 93 the former of which is a vertical and the latter a horizontal mid section. It is now only necessary to cut through the thin retaining-web

of metal at the points d' , extending from the hole D to the end of the link. This may be done after the metal is cold. The links are now separated, but are rough and irregular, as indicated in Figs. 2 and 3. The middle links of the series are here shown irregular purposely to illustrate this. It is necessary now to finish up the links in a die, if it be desired to make a finely-finished chain. This is done in the die or tool illustrated in Figs. 12 and 13, the former of which is a vertical and the latter a horizontal section.

The links may be made of any desired shape—square, circular, oval, or otherwise—and they may have transoms for bracing them, if desired. At the right in Fig. 2 I have shown a link provided with a transom, P, and in Figs. 14 and 15 I have shown a tool for inserting such a transom, the former being a vertical mid-section and the latter a plan of the tool.

Q Q are jaws somewhat like those of a vise, with recesses to receive the link and a loose cross-bar. The transom is placed in position in the link, and the jaws are caused to squeeze the link up on it, so as to grasp it firmly.

In Figs. 2 and 3 is shown the peculiar shape of the cross-section of the rough link after the grooving at J has been effected.

I am aware that it has been proposed to

construct chains from solid bars without a weld, but not in the manner herein described—that is to say, by punching intersecting holes diagonally through the bar from one re-entering angle to that opposite, whereby the metal is cut at the point where the two coupled links join one another or interlink, as shown in Figs. 1 and 2.

Having thus described my invention, I claim—

1. The improvement in the art of making chains from solid bars without a weld, which consists in punching, through a bar formed as described, holes D D, which extend diagonally through from one re-entering angle to the other, and intersect, thereby separating one link from the other at the points where they are coupled together or interlink, as shown and set forth.

2. The tool for piercing the holes D D, constructed and arranged to operate substantially as set forth.

In witness whereof I have hereunto signed my name in the presence of two subscribing witnesses.

EUG. OURY.
